UNITED STATES PATENT OFFICE.

JOHN ALBERT PIERSON, OF MELROSE HIGHLANDS, MASSACHUSETTS, ASSIGNOR TO
GEORGE H. GILMAN, OF BELMONT, MASSACHUSETTS.

HEAT-TREATING MACHINE.

Application filed May 23, 1921. Serial No. 471,864.

My invention pertains to heat treating machines and particularly but not exclusively to machines for heat treating drill steels.

My invention will be best understood from the following description when read in the light of the accompanying drawings of one specific embodiment of my invention selected for illustrative purposes, while the scope of my invention will be particularly pointed out in the appended claims.

In the drawings:

Fig. 1 is a plan with parts broken away of a machine constructed according to my invention;

Fig. 2 is a fragmentary section on the line 2—2 of Fig. 1;

Fig. 3 is an elevation of the carrier looking at it from the right in Fig. 2;

Fig. 4 is an elevation of the lower portion of the carrier looking at it from the right of Fig. 3;

Fig. 5 is a section on the line 5—5 of Fig. 3;

Fig. 6 is a section on the line 6—6 of Fig. 4;

Fig. 7 is a section on the line 7—7 of Fig. 2;

Fig. 8 is a section on the line 8—8 of Fig. 1;

Fig. 9 is a more or less diagrammatic development of the machine; and

Fig. 10 is a more or less diagrammatic plan according to Fig. 9.

Referring to the drawings in which the drill steel is indicated at *a*, I have shown a plate 1, bent in the form of a cylinder and having parallel upper and lower edges 3 and 5 forming tracks for the upper and lower wheels 7 and 9 of the drill steel carriers.

Circumferentially distributed around the machine and under the tracks are a loading table 11, a furnace 12, and a quenching tank 13, the tracks as illustrated by Fig. 9 being at different levels adjacent these instrumentalities, which levels are connected by inclined portions of the track so that the carriers when moved in the direction of the arrow (Fig. 9) move the steels to lower them from the loading table to bring their end portions into the furnace and after removing the end portions of the steels from the furnace lower them into the quenching tank and after passing them through the tank raise them out of the tank and move them

past the mechanism 15 for disengaging the steels from the carriers, the carriers finally being raised to the level of the loading table so that new steels may be placed thereon as the carriers move by the loading table.

The carrier is in the form of a casting having a leg 17 carrying the wheels 7 and 9 and a leg 19 connected to the leg 17 by means of the cross bar 21, the U-shaped structure so formed straddling the track.

At the center of the cylinder formed by the track is a rotatable shaft 23 carrying a turret 25, the latter being provided with an internal portion provided with gear teeth 27, meshing with the pinion 29 carried by a shaft 31 driven by a motor not shown, in any suitable manner. Slidably mounted in bores 33 in the turret are four guide bars 35 carrying on their outer ends heads 37 for engaging the carriers in order that the latter may be propelled around the track. Each guide bar carries a roller 39 held in contact with an undulating circular cam track 41 by means of a compression spring 43, which constantly tends to force the heads 37 outwardly. Extending longitudinally of the outer face of each head 37 is a lug 45 and a lug 47, the latter projecting from the face a greater distance than the former, while for engagement with these lugs each leg 17 of the carriers is provided with the lug 49 extending throughout its length. For guiding the heads, the turret is provided with upstanding guides 51 engaging opposite sides of the head.

The construction of the cam 41 and the general operation of the machine can be best understood by reference to Figs. 9 and 10. The cam 41 is so constructed that both the lugs 45 and 47 of the propeller are caused to engage the sides of the lug 49 of the carrier when the carrier is passing over the loading table. In this position, in a manner herein-after described, the drill steel is placed on the carrier which is immediately moved down the inclined portion of the track to the level above the furnace, where the cam surface 41 causes the propeller to move inwardly in a radial direction to completely disengage the lug 49, the propeller however remaining in engagement long enough to push the row of carriers over the furnace forwardly a distance equal to the width of one carrier, which it is able to do by reason of the fact that the carriers at this time abut each other.

The propeller head now moves by the row of carriers over the furnace until it comes to the last one of the row, whereupon the cam track 41 causes it to move outwardly to 5 cause the lug 47 only of the propeller head to engage the rearward side of the lug 49 of the carrier. This engagement takes place substantially at the time the propeller head immediately following the one under consideration lowers another carrier and drill steel into the furnace and finishes pushing the row of carriers along a distance equal to the width of one carrier in the manner just explained. The carrier at the end of the furnace which has been engaged by the propeller, as has just been described, is pushed along until it reaches the inclined portion of the track leading down to the level of the track above the quenching tank, whereupon 10 it rolls down the inclined portion of the track by gravity advancing ahead of the propeller. When it reaches the end of the incline, it is stopped by means hereinafter described and remains stationary until the 15 propeller again catches up with it, when the cam track 41 causes both lugs 45 and 47 to engage lug 49. The carrier, after moving the drill steel through the quenching tank, reaches the inclined portion leading to the 20 level of the loading table and at this level or immediately before it reaches the level, the steel is disengaged from the carrier by the disengaging mechanism.

For causing the carriers to come to rest 25 when they run down the incline from the furnace to the quenching tank, the turret is provided with four radial outwardly extending arms 53, each of which extends into the path of the projection 55 of the carrier when 30 the latter is at the level corresponding to the beginning of the quenching tank. This arm carries a suitable buffer member in the form of a bolt 57, having a head 59 and a compression spring 61 interposed between the arm 35 and the head. The buffer is so located that it is in proper position for the carrier to strike it immediately upon reaching the bottom of the incline, the portion of the track at this point being preferably horizontal in 40 order to insure the carrier remaining stationary until the propeller head again catches up to it.

As an example of the practice of my invention, but without limitation thereto, I 45 have found it practical to heat the cutting ends of the drill steels for a distance of about four inches back from their end. For quenching them I preferably harden the tip by immersing it suddenly into the quenching 50 liquid, say for example, for about five-eighths of an inch, after which I gradually lower the remaining heated portion into the quenching liquid. For this purpose, the track, except for the short length thereof at 55 the beginning of the quenching tank, is in-

clined downwardly, so that after the carrier begins to move over the quenching tank, it gradually lowers the drill steel into the quenching liquid. It will be noticed that this sudden immersion of the heated end is 70 caused to take place by causing the drill steel to run down the incline to the level above the quenching tank and that the carrier is prevented from moving ahead of the propeller while traveling over the inclined portion of the track above the quenching tank by reason of both lugs 45 and 47 being in engagement with the carrier at that time.

In my present invention the bottom portion of the tank is filled with water or brine and on the same rests a layer of oil of less density than water or brine. The oil preferably is of sufficient depth to cause the tip of the heated end first plunged into the tank to a depth of five-eighths of an inch in the example given, to be quenched exclusively by the oil. Further immersion of the drill steel immediately brings the tip into the water or brine, which acts to keep cool the part which has been quenched by the oil and 90 to quench the remaining portion of the heated end.

For keeping the contents of the tank cool, I provide a cooling coil which is immersed in the liquid. This coil comprises the headers 62 located at opposite ends of the quenching tank and the pipes 64 in fluid communication with the interior of the headers and arranged at opposite sides of the path of the drill steel. A suitable intake 66 is provided for one header and a similar outtake connection for the other, in order that cooling water may be led through the coils.

For holding the drill steels on the carrier, I provide a clamp at the lower end thereof and above this one or more additional gripping means. As illustrated, the intermediate portion and upper end of the carrier leg 19 are provided with the integral projections 63 and with movable clips 65 cooperating with such projections for holding the drill steel therebetween, each clip 65 as shown by Fig. 7 being provided with the flared portion 67, the portion 69 adapted to approximately conform with the surface of the drill steel, and the portion 71 bent to form an eye through which passes the shaft 73 providing a pivot for the two clips. For holding the clips resiliently against the drill steel, I provide the coiled torsion springs 75 through the coil of which the shaft passes and having opposite ends 77 and 79 extended respectively to engage the clip and the body of the leg. The portion 81 of the clip immediately adjacent the portion engaging the drill steel, forms a shoulder which engages the leg to limit the movement of the clip towards the projection 63, the leg adjacent the clips and shaft having a U-shaped recess in which is housed the shaft, the oppo-

site walls of the recess providing abutments for the portion 81 of the clip and the end 77 of the spring. As will be obvious, by pressing the drill steel against the flared portion 67 of the clips, the springs will permit the clips to yield so that the steel may snap into the portion 69 of the clip.

The lower portion of the leg 19 is provided with a projection 83 similar to the 10 projections 63 above, the adjacent portion of the leg being cut away to form half the bearing for the rock shaft 85, the latter being held in position by a bearing block 87 bolted to the leg at 88 and providing the 15 other half of the bearing. On the side of the rock shaft adjacent the drill steel and radially extending from the shaft I provide a jaw 89 for engagement with the drill steel and for securely clamping the steel between 20 it and the projection 83. The opposite side of the rock shaft I provide with a member 91 providing oppositely extending levers 93 and 95, the ends of these levers cooperating with the oppositely inclined cam surfaces 97 25 and 99 provided by inclined surfaces of the wedge-shaped opposite end portions of the vertically sliding member 101.

Slidably mounted on the leg 19 in the lugs 30 103 is a rod 107, the latter carrying an abutment 109 for the spring 111 having its other abutment against the upper lug 103. To this rod is attached the member 101 which is thereby forced by the spring constantly in a direction tending to cause the cam surface 35 97 to engage the lever 93 and to move the jaw 89 into the drill steel engaging position. For causing the jaw to release the drill steel, I provide a stationary cam 113 in the form of a bar supported in any suitable manner 40 and located to have its upper surface in engagement with the lower surface 115 of the member 101 when the carrier is adjacent the disengaging mechanism and during first part of its travel over the loading table.

The disengaging mechanism comprises a standard 116 supporting hooked-shaped cam arms 117 the ends of which are adapted to pass between the leg 19 and the drill steel and by motion of the carrier cause the arms 50 55 to disengage the steel from the gripping means afforded by the clips 67, the arms for this purpose providing surfaces 118 for engaging the drill steel, which are inclined outwardly as is illustrated by Fig. 1. Preferably, the clips 65 are disengaged before the jaw 89 disengages the steel, in order to cause the drill steel to pivot in the clamp afforded by the jaw so that it will fall outwardly away from the machine. For this 60 purpose, the steel engaging surface of the jaw preferably is made smooth and the bar 113 is so located as to delay the release of the jaw until after the clips are disengaged from the steel and the upper end of the steel 65 has moved outwardly some distance. The

bar 113 is provided with a beveled end surface 119 shown diagrammatically in Fig. 3 and in its true position in Fig. 9, for engaging the beveled surface 115 of the cam or wedges carried by the carrier in order that 70 the same may move into engagement with the bar without shock, while the opposite end of the bar over the loading table has a square end in order that the wedges may be released suddenly to cause the jaw to snap 75 into engagement with the steel after the same has been inserted in the carrier and as it passes over the loading table.

Although I have described one form of my invention for purposes of illustration, it is understood that my invention is not limited thereby to particular details of construction but that wide deviations from the same may be made without departing from the spirit of my invention. 85

Claims:

1. In a heat treating machine for the ends of drill steels, a heater, a tank containing a quenching liquid, carriers for the drill steels, a track for said carriers having a downwardly inclined portion for guiding said carriers from said heater to said tank and having a downwardly inclined portion over said tank for causing the drill steels to be immersed gradually in said quenching liquid as the carriers traverse said tank, a propeller for moving said carriers along said track, said propeller having means for pushing said carriers on said first mentioned downwardly inclined portion of said track whereby they run down said inclined portion of said track by gravity advancing faster than said propeller and plunge the tips of the ends of said steels in said quenching liquid and remain stationary until said carrier catches up to them, and means for locking said carriers to said propeller while said carriers move over the second mentioned downwardly inclined portion of said track. 100 105 110

2. In a heat treating machine for the ends of drill steels, a heater, a tank containing a quenching liquid, carriers for the drill steels, a track for said carriers having a downwardly inclined portion for guiding said carriers from said heater to said tank and having a downwardly inclined portion over said tank for causing the drill steels to be immersed gradually in said quenching liquid as the carriers traverse said tank, a propeller for moving said carriers along said track, said propeller having means for pushing said carriers on said first mentioned downwardly inclined portion of said track whereby they run down said inclined portion of said track by gravity advancing faster than said propeller and plunge the tips of the ends of said steels in said quenching liquid, stop means for arresting motion of said carriers when they 115 120 125 130

reach said tank whereby said propeller is enabled to catch up to them, and means for locking said carriers to said propeller while said carriers move over the second 5 mentioned downwardly inclined portion of said track.

3. In a heat treating machine for the ends of drill steels, a heater, a tank containing a quenching liquid, carriers for the 10 drill steels, a track for said carriers having a downwardly inclined portion for guiding said carriers from said heater to said tank and having a downwardly inclined portion over said tank for causing the drill steels to 15 be immersed gradually in said quenching liquid as the carriers traverse said tank, propelling mechanism for advancing said carriers along said track, said mechanism having means for pushing said carriers on said 20 first mentioned downwardly inclined portion of said track whereby said carriers run down said inclined portion by gravity and plunge the tips of the ends of said steels in said quenching liquid, said propelling mechanism 25 having a stop for said carriers for causing them to come to rest upon reaching said tank, and said propelling mechanism locking said carriers thereto for movement on said second mentioned downwardly inclined portion of said track after said carriers 30 remain stationary at said tank for a predetermined time.

4. In a heat treating machine for the ends of drill steels, a heater, a tank containing 35 quenching liquid, carriers for the drill steels, means for moving said carriers to cause them to traverse said heater and tank comprising a downwardly inclined track for guiding said carriers and drill steels from 40 said heater to said tank, said means moving said carriers on said downwardly inclined track and permitting them to run down said track by gravity and plunge the tips of the heated ends of the drill steels in said quenching liquid, said means having a stop moving 45 in the same direction as said carriers when traversing said tank for bringing said carriers to rest when they reach said tank, and said means effecting locking of said carriers 50 thereto after they have remained stationary at said tank for a predetermined time for moving the ends of the drill steels through said quenching liquid.

5. In a heat treating machine for the ends 55 of drill steels, a heater, a tank containing quenching liquid, a closed track traversing said heater and tank, carriers for drill steels movable along said track, propelling mechanism for said carriers comprising carrier 60 engaging members moving generally parallel to said track, said track having a downwardly inclined portion down which said carriers move by gravity to plunge the tips of the ends of drill steels in said quenching liquid and a downwardly inclined portion 65

over said tank for gradually lowering the heated ends of drill steels into said quenching liquid, means for moving said carrier engaging members toward and away from said carriers, said carrier engaging members having a pair of lugs one of which engages said carriers for pushing them on said first mentioned downwardly inclined portion of said track for allowing them to run down said inclined portion by gravity and advance 70 ahead of said members and both of which engage said carriers after said members catch up to them for moving them over the second mentioned inclined portion of said track. 80

6. In a heat treating machine for the ends of drill steels, a heat treating instrumentality, a carrier for moving drill steels to be treated relatively to said instrumentality, means for guiding said carrier, a propeller 85 for moving said carrier along said last named means, and means for connecting and disconnecting said carrier and propeller for respectively enforcing movement of said carrier at the same rate as said propeller and for permitting said carrier at times to move relatively to said instrumentality at a different rate than said propeller. 90

7. In a heat treating machine for the ends of drill steels, a heat treating instrumentality, a carrier for moving drill steels to be treated relatively to said instrumentality, means for guiding said carrier, a propeller for moving said carrier along said last named means, and means responsive to movement 100 of said propeller for connecting and disconnecting said carrier and said propeller for respectively enforcing movement of said carrier at the same rate as said propeller and for permitting said carrier at times to move relatively to said instrumentality at a different rate than said propeller. 105

8. In a heat treating machine for the ends of drill steels, a heat treating instrumentality, a carrier member for moving drill steels to be treated relatively to said instrumentality, means for guiding said carrier, a propeller member for moving said carrier along said last named means, and means responsive to movement of one of said members for connecting and disconnecting said members for respectively enforcing movement of said carrier at the same rate as said propeller member and for permitting said carrier at times to move relatively to said instrumentality at a different rate than said propeller member. 110

9. In a heat treating machine for the ends of drill steels, a heat treating instrumentality, a carrier for moving drill steels to be treated relatively to said instrumentality, means for guiding said carrier, a propeller for moving said carrier along said last named means, means normally connecting said carrier and propeller for preventing 115 120 125

movement of the former faster than the latter relatively to said instrumentality, and means for at times disconnecting said carrier and propeller for causing the latter to push the former along said guiding means and for permitting movement of said carrier faster than said propeller.

10. In a heat treating machine for the ends of drill steels, a heater and a cooler, carriers for moving drill steels to be treated relatively to said heater and cooler, means for guiding said carriers, a propeller for moving said carriers along said last named means, means for normally connecting said carriers and propeller to prevent movement of the former faster than the latter, and means for causing said propeller to advance faster than said carriers when the latter are at said heater and said carriers to advance 20 faster than said propeller when said carriers move from said heater toward said cooler.

11. In a heat treating machine for the ends of drill steels, a heat treating instrumentality, a carrier for moving drill steels 25 to be treated relatively to said instrumentality, a propeller for moving said carrier relatively to said instrumentality having lugs of different length, and means for causing one or both lugs to engage the carrier for 30 respectively pushing said carrier or locking said carrier to said propeller.

12. In a heat treating machine for the ends of drill steels, a heat treating instrumentality, a carrier for moving drill steels 35 to be treated relatively to said instrumentality, a propeller for moving said carrier relatively to said instrumentality having lugs of different length, means for causing one or both lugs to engage the carrier for respectively pushing said carrier or locking said carrier to said propeller, and means for withholding engagement of the carrier by both lugs for permitting said carrier to move at a different rate of speed relatively to said 45 instrumentality than said propeller.

13. In a heat treating machine a heater, a cooler, a carrier for drill steels or the like for moving them relatively to said heater and cooler, means for guiding said carrier to bring said steels progressively into the presence of said heater and said cooler, a propeller for said carrier having means for moving said carrier into said heater and for then disengaging it and causing it to push another carrier out of said heater, means for causing the last named carrier to advance more rapidly than said propeller to bring a steel into the presence of said cooler and then permit said propeller to overtake it, and means for locking said propeller to said carrier when said carrier is in the last named position and is overtaken by said propeller.

14. In a heat treating machine, a quenching tank, a carrier for drill steels or the like for moving them relatively to said tank,

a downwardly inclined track for said carrier adjacent said tank, a propeller for said carrier and having movement lengthwise of said track, and means for connecting said propeller to said carrier when on said track 70 and at other times breaking such connection.

15. In a heat treating machine, a heater and a cooler, a carrier for drill steels or the like, a track for said carrier having a 75 portion adjacent said cooler at a lower level than the portion adjacent said heater and an inclined portion connecting said other portions, means for pushing said carrier out of said heater to cause it to run down 80 said inclined portion, means for propelling said carrier along the portion of said track adjacent said cooler and for locking said carrier to said propelling means.

16. In a heat treating machine, a heater and a cooler, a carrier for drill steels or the like, a track for said carrier having a portion adjacent said cooler at a lower level than the portion adjacent said heater and a connecting inclined portion, propelling 90 means for moving a carrier into said heater and for pushing a carrier out of said heater on said adjacent track portion to cause it to run down said inclined portion, and means for then causing said carrier to remain stationary for a period and for afterwards locking it to said propelling means 95 for moving it along the portion of track adjacent said cooler.

17. In a heat treating machine a heat 100 treating instrumentality, a carrier for moving the article to be treated relatively to said instrumentality, a track for said carrier having an inclined portion and connecting portions at higher and lower levels, a propeller for causing said carrier to run by gravity down said inclined portion, a stop at the lower track level for causing said carrier to come to rest, and means for moving said stop out of the path of said carrier 105 to permit its further movement along said track.

18. In a heat treating machine, a heat 115 treating instrumentality, a carrier for moving the article to be treated relatively to said instrumentality, a track for said carrier having an inclined portion and connecting portions at higher and lower levels, propelling means having a stop projecting into the path of the carrier and at the lower level and having a carrier engaging portion, means for causing said engaging portion to push said carrier down said inclined portion of track to cause said carrier to advance ahead of said engaging portion and be brought to rest by said stop, and means for afterwards connecting said carrier to said propelling means.

19. In a heat treating machine for the 120 ends of drill steels, a heater, a cooler, means 125

for moving drill steels through said heater and cooler comprising carriers for said steels and a downwardly inclined track for guiding said carriers from said heater to said cooler, a propeller for said carriers comprising a rotary member having means for pushing said carriers on said downwardly inclined track and a stop in advance of said means for arresting movement of said carriers after they move down said track by gravity.

20. In a heat treating machine for the ends of drill steels, a heater, a cooler, means for moving drill steels through said heater and cooler comprising carriers for said steels and a circular track for guiding said carriers by said heater and cooler, said track having a downwardly inclined portion for guiding said carriers from said heater to said cooler, a rotary shaft surrounded by said track, a propeller head and a stop carried by said shaft in angularly spaced relation whereby said head may push said carriers on said downwardly inclined portion and said stop may arrest motion of said carriers after they move down said inclined portion by gravity.

21. In a heat treating machine for the ends of drill steels, a heater and a cooler, a circular track traversing said heater and cooler, a carrier for moving the drill steels relatively to said heater and cooler mounted on said track, a propeller for said carrier having a uniform circular movement; and means for varying the rate of movement of said carrier relatively to said heater and cooler comprising mechanism for causing said carrier to be at times connected to said propeller for like movement, at times disconnected from said propeller, and at times to be pushed by said propeller.

22. A heat treating machine for drill steels, having in combination, a heat treating instrumentality, a conveyor for moving said drill steels relatively to said instrumentality, means for fastening said steels to said conveyor, said means comprising a movable jaw having a smooth gripping surface, means for moving said jaw to release said steel, and means for forcibly moving said jaw to grip said steel.

23. A heat treating machine for drill steels, having in combination, a heat treating instrumentality, a conveyor for moving said drill steels relatively to said instrumentality, means for fastening said steels to said conveyor, said means comprising a movable jaw, a lever for moving said jaw, a cam carried by said conveyor for operating said jaw, and means for operating said cam.

24. A heat treating machine for drill steels, having in combination, a heat treating instrumentality, a conveyor for moving said drill steels relatively to said instrumentality, means for fastening said steels to said

conveyor, said means comprising a movable jaw, a lever for moving said jaw, and means carried by said conveyor for actuating said lever to move said jaw for gripping and releasing said steel.

25. A heat treating machine for drill steels, having in combination, a heat treating instrumentality, a conveyor for moving said drill steels relatively to said instrumentality, means for fastening said steels to said conveyor, said means comprising a movable jaw, a cam follower for operating said jaw, cam means cooperating with said follower for moving said jaw to grip and release said steel, and means independent of the conveyor for actuating said cam means.

26. A heat treating machine for drill steels, having in combination, a heat treating instrumentality, a conveyor for moving said drill steels relatively to said instrumentality, means for fastening said steels to said conveyor, said means comprising a movable jaw, and a wedge for operating said jaw.

27. A heat treating machine for drill steels, having in combination, a heat treating instrumentality, a conveyor for moving said drill steels relatively to said instrumentality, of means for fastening said steels to said conveyor, said means comprising a movable jaw, a wedge for operating said jaw, a spring for moving said wedge, means for compressing said spring and for releasing it after such compression to actuate said wedge.

28. A heat treating machine for drill steels, having in combination, a heat treating instrumentality, a conveyor for moving said drill steels relatively to said instrumentality, means for fastening said steels to said conveyor, said means comprising a movable jaw, a spring for operating said jaw, means for compressing said spring and for releasing it to operate said jaw to grip the steel, and means for increasing the mechanical advantage of said spring.

29. A heat treating machine for drill steels, having in combination, a heat treating instrumentality, a conveyor for moving said drill steels relatively to said instrumentality, means for fastening said steels to said conveyor, said means comprising a movable jaw, a pivoted member carrying said jaw, means providing a pair of levers projecting from said member, cams cooperating with each lever, a spring, means for moving one of said cams to operate one of said levers to release said jaw from said steel and to compress said spring, and means for releasing said spring for causing the other of said cams to operate the other of said levers to snap said jaw into engagement with said steel.

30. In a heat treating machine a heat treating instrumentality, a drill steel carrier for moving the drill steels relatively to

said instrumentality, a longitudinally extending shaft supported on said carrier, a plurality of clips for gripping said steel and carried by said shaft, and resilient means for moving said clips toward their steel engaging position.

31. In a heat treating machine, a heat treating instrumentality, a drill steel carrier for moving drill steels relatively to said 10 instrumentality, a clip and a clamp with smooth jaws for gripping a drill steel at spaced points intermediate its length, means responsive to motion of said carrier for pulling said drill steel out of said clip and

15 tilting said steel relatively to said carrier about a point gripped by said jaws, and means for releasing said jaws after said drill steel has tilted.

32. In a heat treating machine for the 20 ends of drill steels, a heat treating instrumentality, a conveyor means for moving drill steels relatively to said instrumentality, means for clamping the drill steels to said conveyor means comprising a jaw, means for actuating said jaw comprising a spring 25 pressed member having the cam surfaces 97 and 99, the levers 93 and 95 cooperating with said cam surfaces, and means responsive to motion of said conveyor means for actuating 30 said spring pressed member.

33. In a heat treating machine for the ends of drill steels, a heat treating instrumentality, a drill steel carrier, a track for guiding said carrier relatively to said instrumentality, a propeller head having the lugs 45 and 47 for engaging said carrier; and means for moving said propeller head relatively to said carrier for causing both lugs 45 and 47 to engage said carrier in one 40 position of said carrier on said track, only the lug 47 in another position, and neither lug in still another position of said carrier.

34. In a heat treating machine for drill steels, a heater for heating the ends only of 45 said steels, a quenching tank containing a body of water having a layer of oil thereon, and means for removing drill steels from said heater and moving them to said quenching tank, said means first placing the tips 50 only of the heated ends of the drill steels into said oil for quenching said tips and afterwards subjecting said heated ends to said water.

35. In a heat treating machine for drill steels, a heater for heating the ends only of 55 said steels, means for removing said steels from said heater and quenching the tips only of the heated ends of the steels in oil and afterwards subjecting said heated ends 60 to water.

36. In a heat treating machine for drill

steels, a heater for heating the ends only of said steels, means for removing said steels from said heater and quenching the tips only of the heated ends of the steels in oil and afterwards gradually subjecting said heated 65 ends to water.

37. In a heat treating machine, a quenching tank containing a body of water with a layer of oil thereon, means for first quenching the tip of a previously heated end of a drill steel in said oil and for afterwards moving said steel through said tank and for gradually immersing said end through said oil into said water. 75

38. In a heat treating machine, a quenching tank, means for moving a drill steel through said tank, and a conduit for cooling fluid at the side of path of said steel.

39. In a heat treating machine for drill 80 steels, a heater for heating the ends of the drill steels, a quenching tank containing a body of water having a layer of oil thereon, means for removing drill steels from said heater and suddenly plunging a predetermined portion of their heated ends in said layer of oil only, said means maintaining said predetermined portion of said heated ends in said oil until said predetermined portion is hardened and then gradually immersing said heated ends in said water. 85

40. In a heat treating machine for drill steels, a heater for heating the ends of the drill steels, a quenching tank containing a body of water having a layer of oil thereon, means for removing drill steels from said heater and suddenly plunging a predetermined portion of their heated ends in said layer of oil only, said means maintaining the drill steels stationary until the portions thereof immersed in said oil are hardened and then moving the drill steels laterally through said tank while gradually lowering their heated ends into said water. 95 100

41. In a heat treating machine for drill 105 steels, a heater, a quenching tank containing a body of water with a layer of oil thereon, means for moving the ends of drill steels through said heater, means for removing the drill steels from said heater and suddenly 110 plunging a predetermined portion of their heated ends in said oil, said means maintaining said predetermined portion of the heated ends in said oil exclusively until said predetermined portions are hardened and then moving the drill steels laterally through said tank while gradually lowering the heated ends into said water. 115

In testimony whereof, I have signed my name to this specification.

JOHN ALBERT PIERSON.
